RAILWAY DRAFT DEVICE

Eugene B. Schrock, Columbus, Ohio, assignor to
The Buckeye Steel Castings Company, Colum-
bus, Ohio

Application July 9, 1931, Serial No. 549,755

2 Claims. (Cl. 213—60)

This invention relates to improvements in railway draft devices, and more especially to a novel striker casting to be employed with a swivel coupler and yoke.

Where a striker consists of a one-piece endless rectangular cast frame, and a carrier iron for a coupler shank, it was heretofore impossible to detach the coupler from the yoke without removing the latter. The primary purpose of the present invention is to provide a striker of such design as to provide clearance for the rear end of the coupler shank while the latter is being installed or removed, so that the coupler may be detached and replaced without first removing the yoke.

Another object is to provide a novel combination of elements involving the coupler shank, yoke and striker, and in which the striker is of such construction as to permit insertion or removal of the rear end portion of the coupler shank through the front aperture of the striker without removing the yoke.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view partly in horizontal section, of the improved combination.

Fig. 2 is a side elevation partly in vertical section.

Fig. 3 is a longitudinal vertical sectional view of the improved striker casting.

Fig. 4 is a front elevation of the same.

Fig. 5 is a top plan view partly in horizontal section, of the striker casting.

Fig. 6 is a fragmentary elevation partly in vertical section, of portions of the yoke, coupler shank and striker casting and illustrating the manner of inserting or removing the coupler.

Figs. 7 and 8 are fragmentary views of portions of the striker casting and coupler shank, and illustrating modified forms of striker castings.

Referring to the drawings, 9 designates the yoke which is supported in the usual manner between the center sills 10 of the car by the conventional supporting iron 11.

Forwardly projecting flanges 12 on the yoke cooperate with rearwardly projecting flanges 13 of the coupler shank 14, and these flanges are pivotally connected by a pin 15.

A horizontal key 16 passes through the rear

end of the shank, the intermediate one of the flanges 12, and through a horizontal notch 17 in the pivot pin, and has its ends extending through horizontal slots 18 in the striker casting 19, and the sills.

As the striker casting is one of the novel elements of the new combination, it will be described somewhat in detail. It comprises an endless cast metal frame substantially C-shape consisting of a top member 20, side members 21 and a rearwardly offset inverted U-shaped bottom member 22, and as best shown in Fig. 3, the top member has a vertical striking web 20a and a lower rearwardly extending flange 20b consisting of a front horizontal portion 23 and rear end portion projecting upwardly and rearwardly, as indicated at 24.

From the side members 21, side walls 25 extend rearwardly and terminate in front draft lugs 25a. These walls have the slots 18 for the horizontal key, and they merge at their upper ends into a roof 26.

Each of the side portions of the casting is provided with an aperture 27a to receive the bolt 28 by which an inverted U-shaped shank supporting wear plate 29 is secured to the striker casting. It will be noted that the lower edges 29a of the wear plate cooperate with the narrow bottom member 22 for reinforcing the depending flanges of the wear plate. The striker casting is reinforced by suitable ribs and has the necessary apertures to receive the rivets employed in uniting the casting with adjacent elements of the car.

From Fig. 2 it will be noted that even if the carrier iron 29 is removed and the pin 15 is detached, the rear end of the shank cannot be passed through the hole in the front of the striker casting, if that casting is made in the usual way. In the conventional striker casting, the flange corresponding with my flange 20b ordinarily extends rearwardly and horizontally from the striking face for the full width thereof. The distance of this flange from the sill tie portion or lower member 22 of the casting may be determined by the normal clearance provided above the coupler stem for maintaining it in alignment, and the width of the flange being determined by the strength of casting desired or the section modulus necessary for the upper portion of the casting. The improved flange has a portion 23 thereof maintained at a distance above the stem of the coupler for holding it in proper alignment, while the rear portion 24 of the flange preferably extends diagonally upward and rearward from the horizontal portion for giving the

necessary clearance for the shoulder 27 to allow for the insertion and withdrawal of the coupler stem, while the yoke is in place and resting on the supporting iron 11. Therefore, in accordance 5 with the present invention, if the carrier iron 29 is detached and the shank is moved forwardly, and its front end is moved downwardly, the shoulder 27 can clear the top of the striker, due to the upturned construction 24 of the rear portion of the flange 20^b, and hence, a dis-connection or connection can be made without removing the yoke 9.

Instead of shaping the flange 20^b as shown in Figs. 1 to 6 inclusive, it may be gently curved upwardly as shown at 24^a in Fig. 7, or if desired, the flange may be straight, as illustrated at 24^b in Fig. 8, and in that case, a bead 24^c will depend from the wall 24^d. The bead 24^c, of course, is at the desired distance above the coupler stem 20 for holding it in proper position, while the flange extending rearwardly therefrom is sufficiently elevated to permit the application or withdrawal of the coupler in the desired manner.

It may be best seen from Fig. 6 that the distance between the front surface of the lug or shoulder 27 and the rear end of the upper one of the flanges 13 is greater than the distance between the rear end of the portion 24 of the striker casting and the front end of the upper one of the flanges 12, and also that there is a slight clearance between the flanges 12 and 13 to permit the coupler shank 14 to be removed through the opening in the striker casting after the carrier iron 29 has been detached.

From the foregoing it will be understood that this invention eliminates a practical difficulty heretofore experienced in installing or removing the shank of a swivel coupling, and so far as I am aware, it has always been the practice in the past to detach the yoke in order to make it possible to remove the coupler shank of swivel couplings.

It is believed from my disclosure that the construction, operation and advantages of the invention may be readily understood by those skilled in the art, and it is manifest that changes may be made in the details disclosed, without departing from the spirit of the invention, as expressed in the claims.

What is claimed and desired to be secured by Letters Patent is:—

1. In combination, a railway car having center sills, a swivel yoke positioned between said sills and having superposed forwardly projecting flanges, a carrier for the yoke connected to the sills, a striker casting arranged at one end of the sills and provided with an annular frame, a coupler shank extending through the frame and having rearwardly projecting flanges intercalated with said forwardly projecting flanges, the space between said forwardly projecting flanges being greater than the thickness of said rearwardly projecting flanges, means connecting the shank and yoke, a carrier iron detachably connected to the striker casting and normally supporting said shank in substan-

tial alignment with the yoke, a shoulder projecting upwardly from said shank, the top portion of said frame having a rearwardly extending flange so arranged as to abut against said shoulder and prevent detachment of the shank from the yoke as long as the shank is in normal alignment with the yoke, the distance between the last mentioned flange and the front surface of the upper one of the flanges of the yoke being less than the distance between the front surface of the shoulder and the rear surface of the upper one of the flanges of the shank, the flange of the yoke which underlies said upper flange of the shank extending forwardly at least as far as said top flange of the yoke, said rearwardly extending flange of the top portion of the frame being of such shape as to provide clearance for said shoulder when the shank carrier iron and the connecting means are removed and the shank is moved forwardly and tipped downwardly, whereby the shank can be detached through said frame without removing the yoke.

2. In combination, a railway car having center sills, a swivel yoke positioned between said sills and having superposed forwardly projecting flanges, a carrier for the yoke connected to the sills, a striker casting arranged at one end of the sills and provided with an annular frame, a coupler shank extending through the frame and having rearwardly projecting flanges intercalated with said forwardly projecting flanges, the space between said forwardly projecting flanges being greater than the thickness of said rearwardly projecting flanges, means connecting the shank and yoke, a carrier iron detachably connected to the striker casting and normally supporting said shank in substantial alignment with the yoke, a shoulder projecting upwardly from said shank, the top portion of said frame having a rearwardly extending flange so arranged as to abut against said shoulder and prevent detachment of the shank from the yoke as long as the shank is in normal alignment with the yoke, the distance between the last mentioned flange and the front surface of the upper one of the flanges of the yoke being less than the distance between the front surface of the shoulder and the rear surface of the upper one of the flanges of the shank, the flange of the yoke which underlies said upper flange of the shank extending forwardly at least as far as said top flange of the yoke, said rearwardly extending flange of the top portion of the frame being of such shape as to provide clearance for said shoulder when the shank carrier iron and the connecting means are removed and the shank is moved forwardly and tipped downwardly, whereby the shank can be detached through said frame without removing the yoke, said striker casting being provided with a striking portion, a downwardly spaced sill tie portion, and portions connecting said striking and sill tie portions, extending rearwardly therefrom, slotted for receiving a draft key adapted to support the front end of the yoke, and formed at their rear portion with front draft lugs.

EUGENE B. SCHROCK.
